BOTTLE

Dennis L. Thomte, 4124 65th St., Urbandale, Iowa, and Andrew R. Tossett, P.O. Box 1546, Minot, N. Dak.

Filed Nov. 2, 1964, Ser. No. 82,417

Term of patent 14 years

(Cl. D58—9)

FIG. 1 is a top plan view of a bottle illustrating our new design;

FIG. 2 is a sectional view as seen on line 2—2 of FIG. 3; and

FIG. 3 is a side elevational view thereof.

We claim:

The ornamental design for a bottle, substantially as shown.
